UNITED STATES PATENT OFFICE.

WILLIAM E. SWEET, OF DOWAGIAC, MICHIGAN.

CARBURETTING APPARATUS FOR INTERNAL-COMBUSTION ENGINES.

1,257,422.

Specification of Letters Patent.

Patented Feb. 26, 1918.

Continuation of application Serial No. 849,758, filed July 8, 1914. This application filed October 19, 1914. Serial No. 867,308.

To all whom it may concern:

Be it known that I, WILLIAM E. SWEET, a citizen of the United States, residing at Dowagiac, in the county of Cass and State 5 of Michigan, have invented certain new and useful Improvements in Carbureting Apparatus for Internal-Combustion Engines, of which the following is a specification.

This invention relates to carbureting apparatus for internal combustion engines. This application is a continuation of my application Serial No. 849,758, filed July 8, 1914.

The objects of this invention are:

15 First, to provide an improved carbureting apparatus by means of which kerosene or a similar hydrocarbon may be used as fuel for internal combustion engines.

Second, to provide an apparatus which 20 can be readily attached to internal combustion engines of standard make by means of which such engines can be run with kerosene or a similar hydrocarbon as a fuel.

Third, to provide an apparatus comprising 25 a pair of carbureters, one supplied with a less volatile and the other with a more volatile hydrocarbon, delivering to the intake manifold of an internal combustion engine and provided with adjusting means so 30 connected together that the adjustment of one of said carbureters to control the mixture thereof will adjust the other carbureter similarly.

Further objects, and objects relating to 35 details and economies of construction and operation will definitely appear from the detailed description to follow.

I accomplish the objects of my invention by the devices and means described in the 40 following specification. The invention is clearly defined and pointed out in the claims.

A structure constituting a preferred embodiment of my invention is illustrated in the accompanying drawing forming a part 45 of this specification, in which:

Figure I is a view in side elevation of an internal combustion engine equipped with my improved apparatus.

Fig. II is a transverse sectional view on 50 the line 2—2 of Fig. I, showing in top plan view the gasoline and kerosene carbureters.

Fig. III is an enlarged detail sectional view on the line 3—3 of Fig. II, showing in detail the three-way valve for controlling 55 the flow of mixture from the carbureters to

the intake manifold, together with the butterfly valve working in the intake manifold.

Fig. IV is an enlarged detail view, partially in section, taken on line corresponding to line 4—4 of Fig. I, showing the connection 60 from the adjusting rod 14 to the carbureters.

In the drawing, similar reference characters refer to similar parts throughout the several views, and the sectional views are 65 taken looking in the direction of the little arrows at the ends of the section lines.

Considering the numbered parts of the drawing, 1 is an internal combustion engine provided with an intake manifold 2 and an 70 exhaust manifold 3. The carbureter 4 has an air intake 5 and a fuel supply pipe 6 which is connected with a fuel supply tank not shown. A second carbureter 7 has an air intake 8 which is connected to the jacket 75 9 extending upwardly and surrounding, for a portion of its length, the exhaust manifold 3 so that the air which is supplied to the air intake 8 flows through the jacket 9 surrounding the exhaust manifold 3 and is 80 heated by the hot gases passing out through the exhaust manifold. The carbureter 7 has a fuel supply pipe 10 which extends rearwardly and is wrapped around the end of the exhaust manifold 3 and is then connected to a fuel supply tank, not shown. The carbureters 4 and 7 are of standard construction with the exception that the butterfly valve which is usually located near the point where the carbureter delivers into 90 the intake manifold has been omitted. Each carbureter is provided with the usual stem 11, extending upwardly therefrom, which controls the needle valve for adjusting the supply of fuel to the carbureter. Upon 95 each stem 11 is secured a disk 12 provided with a plurality of perforations 13. The disk 12 upon the carbureter 4 has connected thereto a rod 14 (see Figs. I and IV) which extends upwardly through the dash 15 and 100 terminates in a thumb nut 16, by means of which the mixture of the carbureter 4 can be controlled. The rod 14 has a pair of projecting prongs at its lower end which are inserted in suitable holes in the disk 12 so 105 as to rotate the same upon the rotation of the rod. The carbureters 4 and 7 can be adjusted independently until the desired mixture is secured. The wire 17 has each end thereof bent up and passed through one 110

115

of the holes 13 in the adjacent disk 12 so that the two disks are connected together and when one of them is turned the other turns with it. By this means the mixture of both carbureters 4 and 7 is controlled by turning the thumb nut 16 on the dash 15.

The carbureters 4 and 7 are connected to the lower end of the intake manifold 2 by means of a three-way valve 18 having a 10 turning plug 19 therein, provided with a passage 20, so that as the plug 19 is turned either the carbureter 4 or the carbureter 7 may be connected with the intake manifold 2, or the plug may be so adjusted that the 15 mixture from both of the carbureters will be delivered to the intake manifold. The plug 19 is turned by means of an arm 21 connected to the end of the link 22 which extends upwardly and rearwardly through 20 the dash 15.

Within the lower end of the intake manifold 2, just above the three-way valve 18, there is provided the butterfly valve 23. This valve is operated by an arm 24 connected by a link 25 to the arm 26 on the throttle control rod 27 which extends upwardly through the dash 15 to a point near the steering wheel in the usual manner.

From the description of the parts given 30 above, the operation of my improved apparatus will be very readily understood. In attempting to use kerosene as a fuel for internal combustion engines difficulty has been met with due to the fact that when the engine is started it is cold and kerosene does 35 not vaporize readily. To overcome this difficulty I employ two carbureters, one of which is connected with a gasoline supply tank or a supply of more volatile hydrocarbon, while the other carbureter is connected 40 to a kerosene supply tank or a supply of less volatile hydrocarbon. The fuel supply pipe running from the kerosene tank to the kerosene carbureter is wound around the 45 rear end of the exhaust manifold so that the supply of kerosene is heated by the hot gases within the exhaust manifold. The air intake of the kerosene carbureter is connected with a jacket which surrounds the 50 exhaust manifold so that the air supply for the kerosene carbureter is heated by the exhaust gases. The two carbureters are connected with the intake manifold by a three-way valve 18. By turning the plug 19 the 55 valve may be so adjusted that the kerosene carbureter 7 is cut off from the intake manifold altogether and only vapor from the gasoline carbureter is delivered into the intake manifold. This is the normal condition 60 when the engine is started, at which time the gasoline vapor is used entirely, the same being delivered from the carbureter 4 into the intake manifold. As the engine warms up the turning plug 19 is gradually 65 rotated to introduce into the manifold less

vapor from the gasoline carbureter 4 and more from the kerosene carbureter 7 until, after the engine has been running awhile, the valve is finally turned so that the gasoline carbureter 4 is cut off entirely and the 70 carbureter 7 is connected so that only kerosene vapor is delivered into the intake manifold and the engine is run upon the kerosene fuel entirely.

The supply of fuel to the carbureters is 75 adjusted from the dash by turning the thumb nut 16 which controls the stem 11 on the gasoline carbureter directly and is connected by means of the wire or link 17 with the disk 12 on the kerosene carbureter 7 so 80 that the same movement is imparted to the disk 12 thereon. The supply of mixture from the three-way valve to the intake manifold is governed by the butterfly valve 23 which is controlled from the throttle of the 85 engine in the manner well known in the art.

The carbureters may be of any standard or desired construction and it is desirable to omit from them the usual butterfly valve. 90 Both the air and the fuel supplied to the kerosene carbureter are thoroughly warmed by the exhaust gases being delivered to the carbureter.

I have described the use of gasoline and 95 kerosene as the hydrocarbon fuels, but it will be understood that this invention is equally applicable with any hydrocarbon fuels, one of which is more volatile than the other. The spirit of my invention contemplates the use of a more volatile fuel for starting and the shifting from the more volatile fuel to the less volatile fuel as the engine warms up after running. While I have specified particularly herein a three 100 way valve, as the invention does not have to do with details of a three way valve but merely to the effect produced thereby, I desire to be understood as claiming not only a three way valve but the equivalent thereof. 105

I am aware that the particular structure I have here shown is susceptible of considerable variation without departing from the spirit of my invention and, therefore, I do not wish to be restricted to the same. 110 I have found, however, that this particular form is to be preferred and, therefore, I desire to claim the same specifically, as well as broadly, as indicated by my appended claims. 115

Having thus described my invention, what I claim as new and desire to secure by Letters Patent, is:

1. In an internal combustion engine, the combination of an exhaust manifold, an intake manifold, a carbureter provided with an air intake, a gasoline supply, a fuel supply pipe connecting said supply with said carbureter, a second carbureter, a jacket surrounding a portion of said exhaust mani- 125 130

fold, an air intake connecting said second carbureter with said jacket, a kerosene supply, a fuel supply pipe connecting said supply with said second carbureter, said fuel supply pipe being coiled around the exhaust manifold for a portion of its length, a three-way valve connecting said carbureters with said intake manifold, said valve being provided with a turning plug, an arm 5 secured to the end of said turning plug, a link extending from said arm upwardly and rearwardly whereby said arm may be actuated, needle valve stems extending upwardly from each of said carbureters, disks 10 secured to each of said stems and provided with a plurality of perforations, a wire link having its ends disposed in one of the perforations of each of said disks and connecting the disks together, a rod connected to 15 the disk on said gasoline carbureter and extending upwardly through the dash whereby the fuel of said carbureter may be adjusted, and a butterfly valve disposed in the intake manifold above said three-way 20 valve and operably connected with the throttle, all coacting substantially as described and for the purpose specified.

2. In an internal combustion engine, the combination of an exhaust manifold, an intake manifold, a carbureter provided with an air intake, a gasoline supply, a fuel supply pipe connecting said supply with said carbureter, a second carbureter, a jacket surrounding a portion of said exhaust manifold, an air intake connecting said second carbureter with said jacket, a kerosene supply, a fuel supply pipe connecting said supply with said second carbureter, said fuel supply pipe being coiled around the exhaust 30 manifold for a portion of its length, a three-way valve connecting said carbureters with said intake manifold, said valve being provided with a turning plug, an arm secured to the end of said turning plug, a link extending 35 from said arm upwardly and rearwardly whereby said arm may be actuated, needle valve stems extending upwardly from each of said carbureters, disks secured to each of said stems and provided with a plurality of perforations, a wire link having its ends disposed in one of the perforations of each of said disks and connecting the disks together, a rod connected to the disk on said gasoline carbureter and extending upwardly 40 through the dash whereby the fuel of said carbureter may be adjusted, all coacting substantially as described and for the purpose specified.

3. In an internal combustion engine, the combination of an intake manifold, a pair 45 of standard carbureters, each of which is provided with a needle valve for controlling the fuel supply having an upwardly projecting needle valve stem, connections from said carbureters to said intake manifold, 50 means for controlling the flow of mixture from said carbureters to said intake manifold, and means for simultaneously rotating said needle valve stems to adjust said needle valves.

4. In an internal combustion engine, the combination of an intake manifold, a throttle valve therein, a plurality of standard carbureters, each complete in itself, one for light hydrocarbon such as gasoline and the other for heavier hydrocarbon such as kerosene, the fuel supply pipe to the carbureter for the heavier fuel being disposed in proximity to the exhaust pipe to be heated thereby, means for simultaneously controlling the fuel supply to said carbureters to regulate the mixture, independent passages from the said carbureters to the intake manifold, a three-way valve for controlling the said independent passages from the carbureters to the manifold whereby the relative amount of mixture from said carbureters can be controlled to the extent of completely cutting off either one or the other, for the purpose specified.

5. In an internal combustion engine, the combination of an intake manifold, a throttle valve therein, a plurality of standard carbureters, each complete in itself, one for light hydrocarbon such as gasoline and the other for heavier hydrocarbon such as kerosene, the fuel supply pipe to the carbureter for the heavier fuel being disposed in proximity to the exhaust pipe to be heated thereby, means for simultaneously controlling the fuel supply to said carbureters to regulate the mixture, independent passages from the said carbureters to the intake manifold, a jacket surrounding a portion of the exhaust pipe of said engine, and an air intake connecting the kerosene carbureter with said jacket, a three-way valve for controlling the said independent passages from the carbureters to the manifold whereby the relative amount of mixture from said carbureters can be controlled to the extent of completely cutting off either one or the other, for the purpose specified.

In witness whereof, I have hereunto set my hand and seal in the presence of two witnesses.
